UNITED STATES PATENT OFFICE.

THOMAS WIGHT, OF KANSAS CITY, MISSOURI.

DESIGN FOR A STREET-ELECTROLIER.

43,488.

Specification for Design.

Patented Jan. 21, 1913.

Application filed November 15, 1912. Serial No. 731,606. Term of patent 7 years.

To all whom it may concern:

Be it known that I, THOMAS WIGHT, a citizen of the United States, residing at Kansas City, in the county of Jackson and State of Missouri, have invented a new, original, and ornamental Design for Street-Electroliers, of which the following is the specification, reference being had to the accompanying drawing, forming part thereof.

The figure is an elevation of a street electrolier, showing my new design.

I claim:

The ornamental design for a street electrolier, as shown.

THOMAS WIGHT.

Witnesses:

LEWIS L. MILLER,

LETA E. COATS.
